HARVESTER-THRESHER AND THE LIKE

Oswald A. Appel, Spokane, Wash., assignor to
Allis-Chalmers Manufacturing Company, Mil-
waukee, Wis., a corporation of Delaware

Application June 9, 1943, Serial No. 490,148

16 Claims. (Cl. 130—21)

This invention relates in general to improvements of utility in connection with threshing apparatus, and it is of special utility in connection with threshers of the harvester-thresher type, for harvesting and threshing grain during the travel of the machine through the field, where the machine is required to operate on ground of variable inclination or slope, and the invention is more particularly concerned with improvements in the mechanism of such machines through which the threshed grain is separated and cleaned, for insuring the depositing of separated grain across the full width of the cleaning shoe independently of the degree of inclination of the machine or the ground over which it is operating.

In harvester-threshers of conventional design, where straw and threshed grain are discharged from the threshing mechanism onto a separating rack which conveys the straw rearwardly, while permitting the passage of separated grain therethrough, to a collecting device from which it is discharged onto the forward edge of a cleaning shoe, when the separating rack and collecting device for feeding the grain to the cleaning shoe assumes a transverse tilt or inclination corresponding to the inclination or slope of the ground on which the machine is working, the major portion of the separated grain is collected at the lowermost side of the tilted collecting device and fed to the cleaning shoe at one side thereof, with the result that the greater part of the separated grain passes over the cleaning shoe along such side, and hence this portion of the cleaning shoe is overloaded and the shoe is not effectively utilized, and the cleaning operation is inefficient, with consequent undue loss of threshed grain.

The present invention contemplates the provision of apparatus embodying a collecting and distributing device through the use of which, particularly in a harvester-thresher, insurance may be provided that the separated grain passing from the separating conveyer or rack of the thresher may be distributed and fed to a cleaning shoe across the full width of the latter, independently of the direction or degree of inclination or tilt of the machine, to the end of insuring efficient utilization of the full screening capacity of the cleaning shoe at all times. A preferred method of obtaining the desired result is through the use of a distributing conveyer which receives the separated grain discharged from the separating rack and insures that the grain is discharged onto the cleaning shoe substantially uniformly across the full width of the shoe; and such apparatus preferably includes a transverse screw conveyer or auger element having flights which are

adjustable to vary the direction and degree or extent of transverse conveying action, to the end of enabling the distributor to distribute the grain substantially uniformly across the full width of the cleaning shoe independently of the direction or degree of slope of the ground on which the machine is working. And a feature of a preferred embodiment of the invention is one wherein the operation of varying the direction and degree or extent of the transverse conveying action of the conveyer is rendered automatic in response to the degree of tilt of the machine or slope of the ground on which the machine is working.

It is an object of the present invention to provide for use in a thresher or harvester-thresher an improved design and construction of separating mechanism embodying a device for insuring the distribution of threshed grain on the cleaning shoe of the machine in a substantially uniform manner across the full width of the cleaning shoe, independently of the degree of transverse tilt of the separating rack or the device for feeding grain to the cleaning shoe.

It is a further object of the present invention to provide an improved design and construction of apparatus of the hereinabove described character, wherein the devices for distributing threshed material onto the cleaning shoe includes a screw conveyer or auger having conveying flights which are adjustable to provide desired variation of the direction and degree of conveying action by the conveyer to thereby secure desired uniformity of distribution of the grain on the cleaning shoe throughout the full width thereof.

It is a further object of the present invention to provide an improved design and construction of apparatus of the hereinabove described character, wherein the inclination or slope of a portion of the machine or of the ground on which the machine is operating is utilized to automatically effect the desired adjustment of conveying action of the conveyer, and particularly as to the direction of conveying and the angularity or pitch of the flights of the conveyer.

These and other objects and advantages are attained by the present invention, various novel features of which will be apparent from the description and drawings disclosing a preferred embodiment of features of the invention, and will be more particularly pointed out in the annexed claims.

In the accompanying drawings:

Fig. 1 is a vertical, sectional view, in a plane through the separator housing, in the direction

of the line of travel, of a harvester-thresher embodying features of the present invention, with parts, not considered essential for present purposes of disclosure, eliminated;

Fig. 2 is a fragmental view in elevation of a portion of the rear side of the harvester-thresher of Fig. 1;

Fig. 3 is a fragmental vertical sectional view in the plane of the line III—III of Figs. 1 and 2, with parts of the conveying device shown in elevation;

Fig. 4 is a fragmental sectional view of the conveying device, in the plane of the line IV—IV of Fig. 5; and

Figs. 5 and 6 are sectional views in the planes of the lines V—V and VI—VI, respectively, of Fig. 3.

Referring to the drawings, wherein the invention is shown as being applied to a harvester-thresher of the type disclosed in United States Patent No. 2,262,453, November 11, 1941, an axle tube 10 serves as the main support for the apparatus, this tube carrying journals for supporting and traction wheels 12. On the supporting axle 10, is mounted a framework carrying a supporting and enclosing housing 15 for the separating mechanism of the harvester-thresher. The left hand side of this housing, as viewed in Fig. 1, is provided with a forwardly extending portion which encloses or houses the threshing mechanism, the latter discharging material rearwardly into the separator housing wherein the straw is advanced transversely of the normal direction of travel of the machine. A rotatable threshing cylinder 17, having spaced peripheral threshing bars 18, has its shaft mounted for rotation in the forward thresher portion of the housing 15, the cylinder bars serving, in conjunction with a stationary concave, to discharge straw and threshed grain from the under side of the cylinder upwardly and rearwardly into the separator housing. Guiding or deflecting vanes or baffles 20 mounted on the roof of the threshing housing, and a guiding or deflecting baffle 21, mounted on the side wall of the housing 15, serve to deflect the discharged material and cause it to drop on the forward end, or end remote from the discharge end, of a separating rack 23 mounted on a plurality of hangers or links 25 and 26 pivotally mounted at their upper ends on the housing 15, links 25 being disposed adjacent the forward portion of the rack and links 26 being attached to a rearward portion thereof, and at their lower ends on the supporting frame of the rack. As indicated, the rack is of a conventional type wherein the supporting frame includes side bars 28, with spaced cross slats 29 secured thereto and extending therebetween. The forward hangers or links 25 may have a baffle associated therewith to prevent threshed grain and straw from passing downwardly through the space between the forward end of the rack and the adjacent side wall of the housing.

Through a pitman connection 31, from an eccentric on the shaft 34 to an arm 35 on the link or hanger 26, the separating rack has imparted thereto a to-and-fro oscillation which serves to advance straw rearwardly along the rack with a shaking motion, thus facilitating dropping of the threshed grain particles through the rack and onto collecting plates or pans 37, 38 beneath the forward and rear portion, respectively, of the rack. The plate 38 is disposed at a higher level than the plate 37. A chain drag 41, having spaced chains passing over driving sprockets 42

on the shaft 34, and guide sprockets 43 on a transverse shaft at the inlet end of the separating housing, is provided with spaced drag or rake bars 45, the bars on the lower course of the chain drag sweeping rearwardly, with respect to the direction of discharge of the straw, along the collecting plate 37 to sweep the threshed grain rearwardly therefrom and over a discharge lip 46 of such plate; and the rake bars on the upper course of the drag sweep forwardly along the collecting plate 38 to sweep threshed grain over a discharge lip 47 thereof. Threshed grain dropping from the separating rack between the discharge lips or edges 46 and 47 of the collecting plates or pans passes directly downwardly through the chain drag. Suitable guides, preferably mounted on the side walls of the housing, are provided for confining the courses of the chain drag to the desired path of travel.

It has been customary in prior devices to discharge threshed grain, collected after passage thereof through the separating rack, directly, or through the intermediary of a discharge chute, onto the forward edge of a cleaning shoe, a conventional form of such a cleaning shoe being indicated at 51, the latter including a supporting frame 52 provided with a plurality of superposed screens, the upper one of which is indicated at 53. Beneath the lower screen of the cleaning shoe is a collecting pan, here shown as a portion of the bottom wall of the housing 15, which conveys clean threshed grain, falling from the cleaning screens, to a hopper or well portion 56 in which a transverse conveyer screw 57, on a shaft 58, operates and serves to convey the clean threshed grain toward a suitable receptacle, such as a conventional form of grain bin mounted on the frame of the machine. The cleaning shoe is flexibly mounted in position through pairs of hangers 59 and 60 pivotally attached at their lower ends to the forward and rear portions of the frame 52 of the cleaning shoe, and pivotally attached at their upper ends to the side walls of the housing 15. The desired oscillating shaking motion is imparted to the cleaning shoe through one or more links 61 pivotally attached to a lower extension of pivoted hanger or lever 26, so that as the pitman 31 imparts shaking oscillation to the separating rack, it imparts corresponding motion to the cleaning shoe.

The upper screen 53 of the cleaning shoe is provided at its rear edge with a conventional form of tailings rack 63 which permits unthreshed or partly threshed grain heads to pass through, while rejecting small particles of straw, the latter passing rearwardly through the discharge end of the separator housing. The tailings which drop through the rack 63 fall into a well or receptacle 64 which may be formed by a portion of the bottom wall of the separator housing; and a conveyer screw 65 in such well is operative to convey the tailings transversely to a point whence they may be conveyed, to the threshing mechanism for rethreshing, by a conventional form of elevating conveyer, provided with a screening device through which is removed clean grain, the latter passing downwardly through a discharge chute 66 for recovery. As indicated, a conventional form of air fan 67, having its shaft mounted in bearings in a fan housing 68 suitably supported on the separator housing on the machine frame, is provided with a discharge passage 69 for supplying air to the cleaning shoe 51 to assist in the cleaning of the grain.

Where gravity alone is relied on to effect the

discharge of the threshed grain, dropping through the separating rack, to the cleaning shoe, with proper distribution of the grain across the full width of the cleaning shoe, reasonably satisfactory results may be expected when the harvester-thresher is operating on level ground, i. e., when the separator housing, and the collecting plates 37, 38 are not inclined in a direction transverse to the length of the separator housing, i. e., the length from left to right as viewed in Fig. 1. However, when such tilting or inclination is present, the major portion of the threshed grain is collected at the lowermost side of the pans and is discharged therefrom onto the corresponding side of the upper screen of the cleaning shoe, with the result that the grain, not being distributed uniformly across the full width of the cleaner, is so disposed on the screen that one side of the screen is overloaded and cannot effectively or efficiently clean all of the grain normally fed to it during the operation of the machine. The loss of grain incident to such an ineffective or inefficient cleaning operation is a major and serious item.

In accordance with a feature of the present invention, the grain discharged from the discharge lip 46 of the collecting pan 37 and from the discharge lip 47 of the collecting pan 38, and likewise the grain dropping directly from the separating rack through the space between the discharge lips 46 and 47, falls into a transverse well or trough 71 suitably supported in position from the side walls of the housing 15, or otherwise. The rear side of the well or trough 71 is provided with a discharge or distributing lip 72 along the full transverse dimension of the cleaning shoe, the grain passing from the well 71 and discharging directly, or preferably by way of a short downwardly inclined chute 73 extending across the full width of the cleaning shoe, to a suitable point on, and adjacent the forward edge of, the upper screen 53 of the cleaning shoe. The lower portion of the trough or hopper 71 is generally of semicircular cross-sectional shape, and the upper portion of the side walls are inclined forwardly and rearwardly.

A screw type conveyer or auger 75 is rotatably mounted, on a transverse axis, within the trough 71, the shaft of the conveyer being in the form of a hollow intermediate body portion 78, shown as being of rectangular cross-section, having end extensions 79 and 80 provided with journal portions. The journal portion of the shaft extension 79 is hollow and is rotatably mounted in a bearing 81 carried by one side wall, i. e., the rear side wall, with respect to the direction of travel of the machine, of the separator housing 15; and the journal portion of the shaft extension 80 is rotatably mounted in a bearing 82 carried by the opposite side wall of the separator housing, or preferably, as indicated, in the corresponding side wall of the enlarged lower portion or discharge well 84 of the clean grain discharge chute 66, this discharge well including a lateral extension suitably secured in an opening in the adjacent side wall of the housing 15, so as to provide communication between this discharge well and the hopper or well 71 disposed within the housing 15. The shaft extension 80 has provided thereon a screw conveyer section 86 which is effective, during normal operation of the conveyer 75, to move clean grain from the discharge well 84 and into the hopper or trough 71. The conveyer shaft 78 is driven by a pulley or sheave 87 mounted on the portion of the hollow journal 79 which pro-

jects beyond the side wall of the separator housing.

The hollow conveyer shaft 78, is shown as comprising opposed parallel walls 88, with a longitudinally extending supporting plate 89 rigidly attached thereto in substantially centralized position, and end plates 90 united to the walls 88 at their ends and carrying the shaft extensions 79 and 80. Hub or spindle portions 91 have their inner ends rotatably mounted in enlarged intermediate bearing portions 92 of the supporting plate 89, these bearing portions being suitably spaced longitudinally of the shaft. And the outer ends 93 of the several hub or spindle portions are rotatably mounted in and project outwardly through the adjacent opposed side walls, indicated at 112, which are at right angles to the plates or walls 88, of the hollow shaft. Sectional conveyer flights 94 are secured, preferably being detachably mounted, on the projecting end portions 93 of the hubs 91, the flights being preferably inserted in slots in said outer end portions. These conveyer flights are of such shape and contour as to sweep fairly closely along the bottom wall of the hopper or trough 71 during rotation of the shaft 78. In the form illustrated, the conveyer flights each consists of a piece of sheet material of the required contour and lying substantially in a single plane, as distinguished from being of warped or curved surface shape.

The hubs or spindles 91 of the conveyer flights 94 are mounted so as to be adjusted to desired angular position to produce a screw conveyer of selected pitch and direction of conveying. As indicated herein, on the hub portion 91 of each of the conveyer flights is provided an arm, or, as shown herein, a pair of spaced parallel arms 96, the arms on the hubs of adjacent conveyer flights extending in opposite directions, and longitudinally extending adjusting rods 97 and 98 are pivotally connected to the arms 96 for actuating or shifting the spindle or hub, with its conveyer flight, on its axis to various angular positions, one of these adjusting rods being provided for each set of alternate flights. The ends of the rods 97, 98 adjacent the rear side wall of the separator housing 15 have loose pivotal connection with a crosshead 101 secured to the inner end of a shaft or spindle 102 which is mounted to slide axially within the hollow journal portion 79 of the shaft 78.

By adjusting the spindle or shaft 102 and its crosshead 101 axially, the actuating rods 97 and 98 may be reciprocated, and through their loose pivotal connection with the arms 96 on the hubs or spindles 91 of the conveyer flights, the sets of alternate conveyer flights are adjusted angularly, in opposite directions, to provide a variable pitch conveyer, and one wherein the direction of conveying may be reversed. As indicated, the outer end of the spindle 102 is provided with a head or journal portion 103 which rotates, in an axially confined manner, in an actuating thrust collar 104 pivotally supported on a link 105, the latter being pivotally connected to a pendulum rod 107 having a pendulum weight 108 adjustably fixed in selected position on the rod. The upper end of the pendulum rod 107 is supported by a hanging link 109 pivoted to the rod and to a supporting brace or structure 110 mounted on the side wall of the separator housing. As the pendulum rod shifts its position from that indicated in Fig. 3, to maintain a vertical direction, the spindle 102 is shifted axially to cause the actuating rods 97, 98 to rotate the hubs

or spindles 91 and the conveyer flights carried thereby in a direction and to an extent dependent upon the direction and extent of the swing of the pendulum with respect to the adjacent side wall of the separator housing 15.

In order to facilitate assembly of the rotatable spindles or hubs of the conveyer flights and the adjusting mechanism therefor within the hollow shaft 78, the opposite side walls 112 through which the spindles 91 extend are preferably made separable from the body of the hollow shaft, i.e., the opposed walls 88 and the supporting plate 89. With such side walls removed, the several conveyer flight hubs or spindles on the corresponding side of the supporting plate 89 may be mounted in position, with the journal portions thereof in their bearings in the supporting wall 89, and the corresponding actuating rod 97 or 98 pivotally secured to the arms 96 on the corresponding alternate hubs and to the crosshead 101 on the spindle 102. The corresponding side wall 112 may then be secured in position, with the outer journal portions of the hubs 91 extending through their bearings in this removable side wall. The hubs or spindles of the other set of conveyer flights may be secured in operative position in their bearings in the opposite side of the intermediate plate 89 and in the opposite removable side wall 112 of the shaft. With the hubs in position, rotatably mounted in the plate 89 and the removable side walls 112 of the shaft 78, and the operating rods 97, 98 pivotally attached to the arms 96 on the several hubs or spindles and to the crosshead 101, and the plates 112 mounted in position, the separate conveyer flights may be attached to the outer projecting ends of the several rotatable hubs.

The various elements of the separating mechanisms are driven from the shaft 58 of the clean grain screw conveyer 57, through belt drives from a sheave 113 on the shaft 58. One driving belt 114 on this latter sheave serves to drive the fan 67, through a sheave 115 on the shaft thereof; and a second driving belt 116 serves to drive the shaft 78 of the reversible and adjustable screw conveyer 75, through a sheave 87 on the hollow journal portion 79 of such shaft, and to drive the tailings conveyer 65, through a sheave 118 on the shaft of the latter conveyer, and to drive the shaft 34, through a sheave 119 thereon, to effect desired driving of the chain drag 41 and the eccentric-actuated pitman 31, the latter serving, through the pivoted crank lever 26, to impart the desired shaking oscillation to the separating rack 23 and the cleaning shoe 51.

In the normal operation of the harvester-thresher through the field, the grain or the like is harvested and conveyed to the threshing mechanism where the action of the rotatable cylinder 17, in conjunction with the stationary concave, threshes the cut grain and discharges straw and threshed grain rearwardly and upwardly therefrom; and through the effect of the baffles or deflectors 20, 21, the material is deposited on the forward end of the separating rack 23 which advances the straw rearwardly to the discharge end, while permitting threshed grain to drop onto the collecting plates or pans 37, 38. The chain drag 41 conveys the threshed grain rearwardly along the plate 37 and forwardly along the plate 38 to their discharge ends 46, 47, respectively; and the grain drops therefrom to the trough or hopper 71 in which the screw conveyer 75 operates.

With the machine operating on ground which does not subject the separator, and more particu-

larly the grain collecting pans 37 and 38 and the grain collecting well or trough 71 to any appreciable tilting transversely of the length of the separator, the grain falls through the separating rack and is collected and is swept by the chain drag 41 uniformly across substantially the full width of the collecting pans or plates 37, 38, and is deposited into and substantially uniformly across the full width or transverse length of the well or trough 71. Under these conditions of operation of the machine on substantially level ground, the grain deposits in the hopper 71 to a level where it overflows the discharge lip 72 and with assistance from the agitating effect of the flights 94 of the conveyer 75, these flights, under such conditions, occupying a substantially neutral conveying position, indicated in full lines in Fig. 3, and exerting minimum axial conveying effect in either direction, the grain is discharged over the discharge lip 72, and onto the discharge chute 73 and the forward edge of the upper sieve 53 of the cleaning shoe. Due to the rectangular cross-section of the hollow shaft 78, the edge or corner portions of this shaft present surface portions which are in effect eccentric with respect to the axis of rotation of the shaft and exert, during rotation, a lifting and rearwardly propelling effect on the grain in the trough 71 to assist its discharge toward and over the discharge lip 72; and this factor or component in the matter of discharging the grain from the well or trough becomes proportionately greater with respect to the effect of the rearward discharging effect of the flights themselves as the latter more closely approach the neutral position, indicated in full lines in Fig. 3. And any clean grain retrieved from the tailings conveyer and discharging, through the chute 66, to the well 84, is conveyed by the screw section 86 into the body portion of the well or hopper 71 where it supplements the grain discharged thereto from the collecting pans 37, 38. As the amount of grain discharged from the chute 66 is relatively small, the addition of this grain from the well 84 to the hopper 71 does not appreciably affect the substantially uniform discharge of grain across the full width of the discharge lip 72 onto the discharge plate 73 and therefrom onto the forward portion of the upper sieve 53 of the cleaning shoe. The general result is that, with the machine operating on level ground, the threshed grain is discharged substantially uniformly across the full width of the cleaning shoe, and no portion thereof is overloaded; and hence effective and efficient cleaning of the grain is secured across the full width of the sieves, with corresponding minimum loss of threshed grain.

When the machine is operating on sloping ground which causes the collecting pans 37, 38 and the hopper or trough 71 to be tilted transversely of the length of the separator, the major portion of the separated grain is discharged from one side of the collecting pans and deposited at one side of the trough 71; and if the flights of transverse conveyer 75 were to remain in the full line neutral position of Fig. 3, the major portion of the grain would be discharged from the lower side of the hopper 71 and onto the corresponding side of the upper sieve 53 of the cleaning shoe, with the result that this side of the cleaning shoe would be overloaded beyond its capacity to do effective and efficient cleaning, and there would be loss of grain, along with the tailings, past the discharge end of the cleaning shoe. However, with the automatically reversible and

adjustable conveyer 75 in operation, and assuming, for instance, that it is the side at the left in Fig. 3 which is in the lowermost position, then through action of pendulum 107, 108 and its effect, through the spindle 102, crosshead 101, and actuating rods 97, 98, operatively connected to the rotatable hubs or spindles 91 of the conveyer flights 94, the angularity of the latter is adjusted in a direction and to such an extent as is required to cause the flights to move the grain from the lowermost side of the well or hopper 71 to the required degree to produce a desired substantially uniform discharge of the grain from the trough 71 onto the discharge plate 73 and the forward edge of the upper sieve 53 of the cleaning shoe, across the full width thereof. As indicated hereinabove, this results in uniform loading of the cleaning shoe across the full width thereof, and hence effective and efficient cleaning of the threshed grain. It will be apparent that, in case the tilting of the separator is in a direction opposite to that described hereinabove, the pendulum 107, 108 will act to cause shifting of the conveyer flights to the required degree in a direction opposite to that heretofore described, to attain the desired uniform distribution of the grain across the full width of the cleaning shoe and effective and efficient cleaning results in the operation of the machine.

Satisfactory results with the above automatically operative distributing conveyer 75 are ordinarily obtainable with an arrangement where the cleaning shoe is relatively fixed as to transverse inclination with respect to the separating rack and collecting pans, and accordingly tilts in the same direction as the separator body, since any transverse sliding of grain on the sieves of the cleaning shoe is ordinarily sufficiently impeded by the roughened surface of the screens alone, or in conjunction with several ridges or barriers on the upper surface of the screens extending longitudinally of the length of the separator housing. However, where the machine is required to work on ground of very considerable degree of slope, further advantages may be attained by using a form of pendulum-operated device for maintaining the cleaning shoe substantially level in spite of the degree of slope of the ground on which the machine is working.

While all of the conveyer flights 94, as hereinabove described, are disclosed as being disposed substantially parallel to each other in neutral position, it will be apparent that one or more of the adjustable vanes or flights adjacent one transverse end of the conveyer, such as that adjacent the end into which the grain discharged from the chute 66 is moved, may, instead of being parallel to the other flights in neutral position have a slight initial set or pitch in such direction as to cause them to convey material away from that end toward the intermediate part of the conveyer.

It will be apparent that the present invention provides a simple and effective arrangement in connection with threshing machines, particularly those of the harvester-thresher type, for greatly improving or increasing the effectiveness and efficiency of recovery of cleaned grain where the machine is required to work on sloping ground. And while the invention has been described in connection with apparatus for the handling of grain, it will be apparent that the invention is of utility in the handling of other food or seed crops and like material.

It will be apparent that the invention disclosed is not limited to the particular features and de-

tails of design and structure described herein and shown in the drawings and that the invention includes such other forms and modifications as are embraced within the scope of the annexed claims.

5 It is claimed and desired to secure by Letters Patent:

1. In a threshing or like apparatus including devices for separating and cleaning threshed grain or the like, a feeding and distributing device disposed in position to receive separated grain and having its discharge edge extending transversely across substantially the full width of said cleaning device adjacent the inlet edge thereof, said feeding and distributing device comprising adjustable conveying means operative to move the separated grain transversely of said feeding device from one side toward the other side thereof when said feeding device is tilted from normal generally horizontal position, and means for varying the direction of conveying by said conveying means of the separated grain to facilitate the distribution of separated grain from said feeding device to said cleaning device uniformly across substantially the full width of said cleaning device irrespective of the direction of transverse tilt of said feeding device.

2. In a threshing or like apparatus including devices for separating and cleaning threshed grain or the like, a feeding and distributing device disposed in position to receive the separated grain and having its discharge edge extending transversely across substantially the full width of said cleaning device adjacent the inlet edge thereof, said feeding and distributing device comprising a receiving element and a conveying device associated with said receiving element, said conveying device being adjustable as to direction of conveying material thereby transversely along said receiving element, and means automatically responsive to the direction of transverse tilt from horizontal of the discharge edge of said receiving device for varying the direction of conveying by said conveying device.

3. In a threshing or like apparatus including devices for separating and cleaning threshed grain or the like, a feeding and distributing device disposed in position to receive the separated grain and having its discharge edge extending transversely across substantially the full width of said cleaning device adjacent the inlet edge thereof, said feeding and distributing device comprising a receiving element and a conveying device associated with said receiving element, said conveying device being adjustable as to rate and direction of conveying of material thereby transversely along said receiving element, and means automatically responsive to the direction of transverse tilt from horizontal of said feeding and distributing device for varying the rate and direction of conveying by said conveying device to enable said feeding and distributing device to discharge the separated grain in a substantially uniformly distributed stream to and across the full width of said cleaning device.

65 4. In a threshing or like apparatus including devices for separating and cleaning threshed grain or the like, a feeding and distributing device comprising a trough disposed in position to receive the separated grain and having its discharge edge extending transversely across substantially the full width of said cleaning device adjacent the inlet edge thereof, and a conveying device within said trough and provided with flights adjustable as to direction of conveying, means for adjusting said conveyer flights as to

direction of conveying thereby, said means including a pendulum device operative in response to the direction of transverse tilt from horizontal of the discharge edge of said feeding device to cause said conveying device to convey material from the lowermost transverse side of said trough toward the opposite side thereof at a rate which provides for the discharge of material from said trough in a substantially uniform stream across substantially the full width of said cleaning device.

5. In a threshing or like apparatus including devices for separating and cleaning threshed grain or the like, a feeding and distributing device disposed in position to receive the separated grain and having its discharge edge extending transversely across substantially the full width of said cleaning device adjacent the inlet edge thereof, said feeding and distributing device comprising a trough and a conveying device within said trough and provided with flights adjustable as to direction and rate of conveying, means for adjusting said conveyer flights as to rate and direction of conveying thereby, said means including a pendulum-operated device operative in response to the direction and degree of transverse tilt of the discharge edge of said feeding and distributing device to cause said conveying device to convey material from the lowermost side of said trough toward the other side thereof at a rate which facilitates the discharge of material therefrom in a stream substantially uniformly distributed across substantially the full width of said cleaning device.

6. In a threshing or like apparatus including devices for separating and cleaning threshed grain or the like, a feeding and distributing device comprising a trough disposed in position to receive the separated grain and having its discharge edge extending transversely across substantially the full width of said cleaning device adjacent the inlet edge thereof, and a conveying device in the form of a screw conveyer within said trough and including a rotatably mounted shaft having a hollow body portion, conveyer flights pivotally mounted on said hollow shaft portion and having pivotal spindles projecting into the interior of said hollow shaft portion, actuating elements within said hollow shaft portion and cooperating with said spindles, and operating means cooperative with said actuating means and projecting from said hollow shaft portion to and operable from the exterior thereof while said shaft is in operation to effect desired adjustment of the pitch and direction of conveying of said flights.

7. In a threshing or like apparatus including devices for separating and cleaning threshed grain or the like, a feeding and distributing device comprising a trough disposed in position to receive the separated grain and having its discharge edge extending transversely across substantially the full width of said cleaning device adjacent the inlet edge thereof, and a conveying device in the form of a screw conveyer within said trough and including a rotatably mounted shaft having a hollow body portion, conveyer flights pivotally mounted on the hollow portion of said shaft and having pivotal spindles projecting into the interior of said hollow shaft portion, alternate flights in the direction of the axis of said shaft being mounted at radially opposite sides of the shaft, actuating elements within said hollow shaft portion and cooperating with said spindles, operating means cooperative with said actuating means and including a spindle project-

ing from and axially adjustable through one end of said hollow shaft, and a pendulum-actuated device responsive to the degree of tilt from horizontal of the axis of rotation of said shaft for actuating said axially adjustable spindle to effect predetermined angular adjustment of said conveyer flights as to rate and direction of conveying to cause said feeding device to feed the separated grain to said cleaning device substantially uniformly across the full width of said cleaning device.

8. In apparatus of the character described, a conveyer comprising a trough adapted to receive material and having an open discharge side, a shaft mounted to rotate in said trough and having a hollow body portion, conveyer flights rotatably mounted on said hollow shaft portion to different positions of angular adjustment and having pivotal mounting spindles projecting into the interior of said hollow shaft portion, means associated with the mounting spindles of said flights for rotating said flights about the axes of their spindles, said means comprising actuating elements within said hollow shaft portion, operating means cooperative with said actuating means and projecting from said hollow shaft portion to the exterior thereof, and a pendulum-actuated device responsive to the degree of tilt of the axis of rotation of said shaft for actuating said operating means to effect predetermined angular adjustment of said conveyer flights.

9. In apparatus of the character described, a conveyer comprising a trough adapted to receive material throughout substantially its full length and having an open discharge side, a shaft mounted to rotate in said trough and having a hollow body portion, conveyer flights pivotally mounted on the hollow portion of said shaft and having pivotal mounting spindles projecting into the interior of said hollow shaft portion, alternate flights along the length of said shaft being mounted at radially opposite sides of the shaft, means associated with the mounting spindles of said flights for rotating said flights about the axes of their spindles, said means comprising actuating elements within said hollow shaft portion, a spindle projecting and axially adjustable through one end of said hollow shaft and operatively connected to said actuating elements within said shaft, and a pendulum-actuated device responsive to the degree of tilt of the axis of rotation of said shaft in either direction from a normal horizontal direction for actuating said spindle to effect predetermined angular adjustment of said conveyer flights.

10. In a harvester-thresher, comprising harvesting, threshing and separating mechanisms, and a cleaning shoe adapted to receive separated grain or the like and chaff adjacent its inlet edge and to advance chaff to the discharge edge of the shoe, said separating mechanism and said cleaning shoe being enclosed within and supported by an enclosing housing, a trough within said housing extending transversely of the direction of travel of chaff over said cleaning shoe and adapted to receive grain and chaff, said trough having a discharge adjacent the inlet side of said cleaning shoe across substantially the full width thereof, an adjustable conveyer within said housing having flights operating within said trough and operative to convey material along said trough and to cause the discharge of the material from said trough onto the adjacent edge of said cleaning shoe across substantially the full width thereof, and means

responsive to the direction and degree of tilt of said conveyer trough from a generally horizontal direction to automatically vary the pitch and reverse the direction of said conveyer flights to insure the feeding of grain from said trough to said cleaning shoe across substantially the full width thereof independently of the direction and degree of tilt of said trough.

11. In a harvester-thresher, comprising harvesting, threshing and separating mechanisms, and a cleaning shoe adapted to receive separated grain or the like and chaff adjacent its inlet edge and to advance chaff to the discharge edge of the shoe, said separating mechanism and said cleaning shoe being enclosed within and supported by an enclosing housing, a trough within said housing extending transversely of the direction of travel of chaff over said cleaning shoe and adapted to receive separated grain and chaff, said trough having a discharge adjacent the inlet side of said cleaning shoe across substantially the full width thereof, a conveyer operatively supported by said housing and having adjustable flights operating within said trough and operative to convey material along said trough in either direction, and pendulum-actuated means supported by said housing and responsive to the direction and degree of tilt of said conveyer trough from a generally horizontal direction to automatically vary the rate and reverse the direction of conveying of said conveyer to insure the feeding of grain from said trough to said cleaning shoe across substantially the full width thereof.

12. In a harvester-thresher, comprising harvesting, threshing and separating mechanisms, and means including a cleaning shoe adapted to receive separated grain or the like and chaff adjacent its inlet edge and to advance chaff to the discharge edge of the shoe and to recover partly threshed tailings for supply thereof to the threshing mechanism for rethreshing, a housing enclosing and supporting said separating and cleaning mechanisms, a trough within said housing extending transversely of the direction of travel of chaff over said cleaning shoe and adapted to receive grain and chaff from said separating mechanism, said trough having a discharge adjacent the inlet edge of said cleaning shoe across substantially the full width thereof, means for collecting clean grain separated from said tailings during the passage thereof to said threshing mechanism, said collecting means comprising a discharge well communicating with one end of said trough, a rotatably mounted screw type conveyer having conveying flight sections operating in said trough and said discharge well, respectively, the conveying section in said discharge well being operative to convey material from said well into said trough under all conditions of operation, and the conveying section in said trough comprising flights angularly adjustable on said shaft to vary the pitch and direction of conveying of said latter flights, and gravity actuated means responsive to the direction and degree of tilt of said screw conveyer from a generally horizontal direction to automatically vary the rate and reverse the direction in which said conveyer conveys material along said trough and feeds said material to said cleaning device to insure the distribution of grain from said trough to said cleaning shoe across substantially the full width thereof.

13. In apparatus for feeding grain or the like in a stream of extended width, a feeding and distributing device disposed in position to receive the grain and comprising a trough having a discharge edge extending across substantially the full length of said trough, a conveying device rotatable within said trough and having conveying flights thereon adjustable as to direction of conveying material thereby along said trough, and means automatically responsive to the direction of transverse tilt from horizontal of the axis of rotation of said conveying device for varying the position and conveying effect of said conveying flights.

14. In apparatus for feeding grain or like material in a stream of extended width, a trough adapted to receive material to be fed and having an open discharge side, a screw type conveyer disposed within and extending longitudinally of said trough and mounted to rotate therein, said conveyer comprising a shaft having a hollow portion, and external conveying flights mounted on the hollow portion of said shaft, said flights being adjustable to vary the pitch and the direction of conveying of said flights, and the hollow portion of said shaft being provided with peripheral surface portions between said flights operative to propel material within said trough toward the discharge side thereof during rotation of said conveyer.

15. In a threshing or like apparatus including a device for cleaning threshed grain or the like, a feeding and distributing device comprising a trough disposed in position to receive the grain and having its discharge edge extending transversely across substantially the full width of said cleaning device, and a conveying device in the form of a screw conveyer within said trough and including a rotatably mounted shaft having a hollow body portion, conveyer flights pivotally mounted on the hollow portion of said shaft and having pivotal spindles projecting into the interior of said hollow shaft portion, actuating elements cooperating with said spindles for angularly adjusting the same, operating means cooperative with said actuating means, and a pendulum-actuated device responsive to the degree of tilt from horizontal of the axis of rotation of said shaft for actuating said operating means to effect predetermined angular adjustment of said conveyer flights as to rate and direction of conveying to cause said feeding device to discharge the grain substantially uniformly across the full width of the discharge edge of said trough.

16. In apparatus for feeding and distributing grain or the like, a conveyer comprising a trough like element adapted to receive material and having an open discharge side, a shaft mounted to rotate in said trough and having a hollow body part, conveyer flights rotatably mounted on said hollow shaft part and adjustable to different positions of angular adjustment and having pivotal mounting spindles projecting into the interior of said hollow shaft part, and adjusting means disposed within said hollow shaft portion and operative to adjust the angular position of said conveyer flights, said hollow shaft part having peripheral surface portions between adjacent flights and eccentric with respect to the axis of rotation of said shaft and operative to propel material within said trough toward the discharge side thereof during rotation of said shaft.
